DESIGN FOR A PICTURE PROJECTOR HOUSING

William Mack, Chicago, Ill., assignor to The
Bell & Howell Company, Chicago, Ill., a cor-
poration of Illinois

Application June 18, 1940, Serial No. 93,076

Term of patent 14 years

To all whom it may concern:

Be it known that I, William Mack, a citizen
of the United States, residing at Chicago, in the
county of Cook and State of Illinois, have in-
vented a new, original, and ornamental Design
for a Picture Projector Housing, or which the fol-
lowing is a specification, reference being had to
the accompanying drawing, forming a part
thereof.

In the said drawing—

Figure 1 is a side elevation of a picture pro-
jector housing embodying my new design;

Figure 2 is a rear elevation;
Figure 3 is a top plan view;
Figure 4 is a side elevation taken oppositely
with reference to Figure 1; and
Figure 5 is a front elevation.

I claim:

The ornamental design for a picture projector
housing, as shown.

WILLIAM MACK.
